UNITED STATES PATENT OFFICE.

ASA WRIGHT, OF LONG BEACH, CALIFORNIA.

ADJUSTABLE WIRE BRUSH.

1,382,042.

Specification of Letters Patent. Patented June 21, 1921.

Application filed October 27, 1920. Serial No. 419,864.

To all whom it may concern:

Be it known that I, ASA WRIGHT, a citizen of the United States, residing at Long Beach, in the county of Los Angeles and 5 State of California, have invented a new and useful Improvement in an Adjustable Wire Brush, of which the following is a specification.

This invention relates to a wire brush having the bristles secured to a head in combination with a socket handle, so arranged that the projection of the bristles beyond the socket can be adjusted.

One common use of wire brushes is for 15 cleaning paint, grease, and other foreign matter from metallic surfaces to prepare them for soldering, brazing, and the like. Such use places a great strain on the bristles at their points of support by the handles or heads, and with a relatively long bristle between the point of support and free end, the brush bristles spread requiring a great effort to clean the surface and causing many bristles to break off. Brushes of 20 this character in general use comprise the ordinary handle with long bristles attached thereto. It has been the common practice for users of such brushes to place a band about the bristle body, midway between the 25 head and free ends of the bristles so as to give greater rigidity to the bristles and decrease spreading. The band is generally metallic and held against slipping by securing it to the head or handle. After the bristles 30 have worn down, the band is removed and the brush used in its original condition. It is obvious that time and labor are required to place and remove the band, that when the bristles are finally worn down, the handle 35 must be discarded along with the bristles.

It is the primary object of this invention to overcome these objections and to provide a brush structure such that the desired length of bristles may project beyond the support 45 for the most efficient use, and that the bristles may be adjusted to compensate for wear. It is another object of this invention to provide a handle and head carrying bristles which may be detachably and adjustably secured to a handle, the bristles and head being renewable. In addition to the broader objects of this invention, there are certain 50 details of structure, whereby a simple, easily manipulated and strong construction is obtained.

These objects together with other objects

and corresponding accomplishments are obtained by means of the embodiment of my invention illustrated in the accompanying drawing, in which:

Figure 1 is an elevation of the complete brush in assembled form; Fig. 2 is a section as seen on the line 2—2 of Fig. 1; Fig. 3 is a section as seen on the line 3—3 of Fig. 2; and Fig. 4 is a fragmentary section 65 on an enlarged scale as seen on the line 4—4 of Fig. 3.

The brush comprises a hollow handle and socket A, a head and bristles B and a detachable shank C. The head and shank are 70 secured to each other in assembling the brush and disposed within the handle.

The wire bristles 5 are clamped in a head or carrier having a band portion 6 clamping the bristles and an extension 7. The extension 7 is preferably formed with fingers 8. The fingers are adapted to be bent and inserted through a slot in the head 9 of the shank. The portion 10 of the shank extends into the handle proper of the brush and is 80 provided with a row of apertures 11.

The handle comprises a socket portion 12, in which the bristles and head are disposed. The handle portion 13 may be of any shape suitable for convenient manipulation of the 85 brush. At the juncture of the handle and socket is an opening to receive a screw 14. This opening is so placed that the apertures 11 in the shank may be made to register with it. On the side of the handle there is a 90 raised portion 15 about the opening so that threads may be cut therein. The head and bristles are attached to the shank, and they are then inserted in the handle. The bristles are adjusted to project the desired 95 amount beyond the mouth of the socket, with one of the apertures 11 in registration with the opening in the handle. A screw 14 forming a locking pin is then placed in position securely locking the shank, head and bristles 100 in position. The brush is now ready for use, and as it wears down toward the socket, the bristles may be further projected by removing screw 14 and bringing the shank to a position such that an aperture registers with 105 the opening.

When the bristles have been worn down close to the head, the shank, carrier, and bristles are removed from the handle. The fingers 8 are then bent so that the carrier 110 may be detached from the shank, and a new carrier and bristles secured thereto. It is

obvious that the handle and shank may be retained as permanent parts of the structure, while the carrier and bristles may be renewed. Thus, renewal of the brush is inexpensive.

What I claim is:

1. A brush structure comprising the combination of a socket having an aperture, a detachable head slidably mounted in said 10 socket, said head having a series of apertures for registration with the aperture of said socket, a bristle carrier detachably secured to said head, and a pin for insertion in registering apertures whereby the 15 projection of the bristles may be adjusted.

2. A brush structure comprising the combination of a hollow handle having a socket, a head having bristles secured thereto slidably mounted in said socket, said head having bendable fingers, a shank detachably secured to said head by passing the fingers through an opening therein and mounted within said handle, and means to adjustably secure said shank to said head, whereby to project the bristles as the brush wears.

In witness that I claim the foregoing I have hereunto subscribed my name this 12th day of October, 1920.

ASA WRIGHT.
